UNITED STATES PATENT OFFICE

166,264

STOCKING

William M. Langer, Berlin, N. J.

Application October 5, 1951, Serial No. 16,841

Term of patent 14 years

(Cl. D47—7)

To all whom it may concern:

Be it known that I, William M. Langer, a citizen of the United States, residing in Berlin, in the county of Camden and State of New Jersey, have invented a new, original, and ornamental Design for a Stocking, of which the following is a specification, reference being had to the accompanying drawing, forming part thereof.

In the drawing, Fig. 1 is a side elevational view of a stocking embodying my new design; Fig. 2 is an enlarged, fragmentary, rear elevational view of a stocking embodying my new design; and Fig. 3 is an enlarged fragmentary side elevational view embodying my new design.

I claim:

The ornamental design for a stocking, as shown.

WILLIAM M. LANGER.
